BRAKE SHOE

Adolph Rosner, South Bend, Ind., assignor to
 Bendix Brake Company, South Bend, Ind., a
 corporation of Illinois

Application April 21, 1930, Serial No. 445,870

2 Claims. (Cl. 188—250)

This invention relates to internal expanding brakes and more particularly to the friction or braking element thereof.

An object of the invention is to provide a friction element possessing great strength and rigidity.

Another object of the invention is to provide a friction element for a brake constructed from relatively thin or light material, and yet possessing great strength and rigidity.

A further object of the invention is to provide a friction element for a brake in which the web is corrugated and deformed to the radius of the rim.

Yet a further object of the invention is to provide a friction element for a brake having a strengthening web or corrugated material deformed and secured by one edge thereof to the rim.

Still a further object of the invention is to provide a method for the manufacture of a friction element for a brake, wherein the reinforcing web of the element may be stamped from sheet material crimped or corrugated and deformed to the radius of the rim of the element.

Other objects of the invention will appear from the following description taken in connection with the drawing, which forms a part of this specification, and in which:

30 Figure 1 is a side elevation of a brake shoe embodying the invention;

Figure 2 is a plan view of the back of the shoe;

Figure 3 is a plan view of a stamping from which the web is formed having reinforcing plates secured to its respective ends;

Figure 4 is a sectional view of the stamping shown in Figure 3 after it has been crimped or corrugated;

Figure 5 is a sectional view of a rim and the strengthening web after they have been formed;

Figure 6 is a similar view illustrating the rim and web welded together; and

Figure 7 is a sectional view substantially on line 7—7, Figure 3, illustrating the reinforcing clip for the anchor portions of the shoe.

Referring to the drawing for more specific details of the invention, 10 represents generally a friction element or a shoe for an internal expanding brake. As shown, the shoe comprises a rim 11 having secured thereto a suitable lining 12. The rim is reinforced by a corrugated web 13 having positioned on its respective ends reinforcing clips 14 apertured as indicated at 15 and 16 to receive an anchor and an articulating connection not shown.

The web 13 is stamped from sheet metal first in the form of a blank 17. This blank has suitably secured to its respective ends as by spot welding the reinforcing members 14. These members are preferably made of sheet metal bent

upon themselves as shown in Figure 7 to fit snugly on the ends of the blank 17. The reinforcing members 14 together with the ends of the blank are apertured as at 15 and 16 for the purpose hereinbefore specified. The blank is then corrugated substantially as shown in Figure 4.

Assuming that the rim 11 has been previously bent or formed to the desired arc, the web is then deformed to the radius of the rim substantially in the form shown in Figure 5. In deforming the web to the radius of the rim that portion lying immediately adjacent to the inner periphery of the rim will be extended or stretched to a greater or less degree, whereas that edge farthest from the inner periphery of the rim will be compressed. Hence, the corrugations of the web will be contracted in pitch at the inner periphery of the web and expanded at the opposite edge. This produces a web having a tapering cross section.

This is due to stretching that portion of the web adapted to engage the rim and compressing that portion or edge of the web farthest removed from the rim. Upon deforming the blank 17 to conform to the rim, it takes the shape illustrated in Figure 5, after which it is spot welded to the rim, as indicated at 18.

A friction member or shoe provided with a web of this character possesses great strength and rigidity and that by virtue of the particular form of web, the friction member or shoe as a whole may be manufactured from comparatively light sheet metal, accordingly great saving in the cost of production is effected.

Although this invention has been described in connection with certain specific embodiments, the principles involved are susceptible of numerous other applications that will readily occur to persons skilled in the art. The invention is, therefore, to be limited only as indicated by the scope of the appended claims. The method of manufacture described above is claimed in my divisional application No. 634,040, filed September 20, 1932.

Having thus described the various features of the invention, what I claim is new and desire to secure by Letters Patent is:

1. A friction member comprising a rim, a lining secured to the rim, a corrugated web secured to the rim and plates bent upon themselves and fitted on the respective ends of the web.

2. A friction element comprising a rim, a lining secured to the rim, a reinforcing corrugated web spot welded to the rim, the respective ends of the reinforcing web being positioned in the same plane and apertured, reinforcing plates bent upon themselves to embrace the respective ends of the web, the reinforcing plates having apertures coinciding with the apertures in the respective ends of the web.

ADOLPH ROSNER.
